RAILWAY SIGNALING SYSTEM

Andrew Langdon, Brighton, N. Y., assignor to
General Railway Signal Company, Rochester,
N. Y.

Application November 16, 1944, Serial No. 563,674

11 Claims. (Cl. 246—41)

This invention relates to railway signaling systems, and more particularly pertains to the provision of track circuits in connection with crossovers between adjacent parallel tracks.

In most track circuit arrangements now in use in connection with crossovers, it is possible for a single car or locomotive to occupy a dangerous position on the crossover without setting the signals on the adjacent parallel tracks at stop. The reason for this is that, since adjacent parallel tracks are usually so close together, the provision of insulated joints at the mid-point of the crossover does not represent the actual fouling or clearance point of the cross over. Thus, if a train proceeds over the crossover and just passes the insulated joints at the mid-point of the crossover, the main track which the train has just left may still be fouled by the rear end of such train because of the closeness of the crossover track to the main track.

In view of the above considerations, it is proposed in accordance with the present invention to provide an improved track circuit organization in connection with a crossover whereby a car or locomotive on any part of the crossover will place the signals of both parallel tracks at stop and maintain such condition until the train wholly leaves the track sections including the crossover irrespective of the position of the switches.

It is further proposed that the turnout fouling rail for each track of the crossover shall be associated with the detector track circuit for its associated main track in such a way as to provide broken rail protection without requiring any additional apparatus.

A still further object of the invention is to provide the proposed track circuit organization for the crossover in such a way that the continuity of the right-of-way track circuits shall be controlled in accordance with the condition of crossover detector track circuits to thereby avoid inserting the detector track circuit control into the regular signaling line circuits. It will of course be obvious that such an arrangement is particularly adaptable for use with relatively long coded track circuits for the right-of-way where there are no line wires.

Other objects, purposes and characteristic features of the present invention will be in part obvious from the accompanying drawing, and in part pointed out as the description of the invention progresses.

In describing the invention in detail, reference will be made to the single accompanying draw-

ing which illustrates one embodiment of the present invention employing conventional direct current track circuits of the normally closed circuit type.

5 In the drawing, two parallel adjacent tracks A and B are shown, and it is assumed for convenience in the disclosure that track A is for west bound traffic and that track B is for east bound traffic.

10 The track A is shown as having a right-of-way or regular signaling track circuit with the usual track battery 5 and track relay TA separated from the rest of the stretch of track by the usual insulated joints. This right-of-way track circuit is divided into two parts including track section 6 and track section 7, by reason of insulated joints forming a detector track section DA associated with the switch SA at the left-hand end of the crossover. This detector track section DA has a track battery 9 and a track relay TDA included in the track circuit, as will be presently described.

15 Similarly, the track B has a right-of-way track circuit with a track battery 10 and a track relay TB which track circuit is divided into sections 11 and 12 by reason of the insulating joints forming the detector track section DB associated with the track switch SB at the right-hand end of the crossover. The detector track section DB has a usual track battery 13 and a track relay TDB associated therewith, as will be presently described.

20 Each of the track switches SA and SB are assumed to be of the usual manually operated type having associated therewith the switch stands 14 and 15 respectively. These switch stands 14 and 15 for the purpose of the present embodiment of the invention are considered to be of the conventional hand-operated type of switch stand, but it is to be understood that the principles of the present invention may be readily applied to a crossover having power-operated track switches at its opposite ends.

25 Each of the switches SA and SB is provided with suitable switch box or circuit controller contacts SCA and SCB respectively. These switch circuit controller contacts may be operated by any suitable mechanism, such as shown for example in the prior Patent No. 1,899,894 granted 30 to O. S. Field on February 28, 1933, but it is to be understood that any suitable contact mechanism may be employed providing that the contacts associated therewith are closed in their normal positions shown only when the corresponding switch is in a normal locked position.

and which contacts are opened whenever the track switch is unlocked and in an intermediate or reverse position.

Referring to the switch SA, it will be seen that the movable point 16 is bonded to the running stock rail 17 by a suitable bond connection 18; while an insulated joint 19 is located between the heel of such movable point and the switch frog. The other movable point 20 is normally held against the turnout stock rail 21 and is bonded thereto by a suitable bond connection 22. Insulated joints 23 are located at the midpoint of the crossover rails, and the crossover rail associated with the frog of switch SA is suitably bonded to the running rail 24. An insulated joint 25 is placed in the turnout stock rail 21 opposite the insulated joint 19 so that there will be no dead section as between the turnout stock rail 21 and the movable point 16. The insulated joints 23 and 25 thus form a turnout fouling rail 26 associated with the switch SA.

A similar set of insulating joints are associated with the switch SB at the right-hand end of the crossover, as well as a similar arrangement of bonding. Particular attention is directed to the fact that an insulated joint 27 is included in the turnout stock rail 28 near the switch SB so as to be opposite the insulated joint 29 included in the movable point rail 30. These insulated joints 23 and 27 thus form a turnout fouling rail section 31 associated with the switch SB.

The detector track relays TDA and TDB have associated therewith a stick relay S which has a suitable battery source 32 provided for energizing its pick-up and stick circuits, as will be presently described.

Under normal conditions of traffic, the track switches SA and SB are in normal positions for main line traffic, and with such prevailing normal conditions, the detector track relays TDA and TDB are normally energized.

More specifically, the detector track relay TDA is energized by a circuit closed from the positive terminal of the track battery 9, through the upper rail 17 of track A, bonding connection 33, turnout fouling rail 26, contact 34 of switch circuit controller SCA in a normally closed position, windings of detector track relay TDA, contact 35 of switch circuit controller SCB in a normally closed position, the lower rail 24 of main track A, to the negative terminal of the battery 9.

Similarly, the detector track relay TDB is energized over a track circuit from the positive terminal of the battery 13, lower rail of track B, bonding connection 36, turnout fouling rail 31, contact 37 of switch circuit controller SCB in a normal position, windings of detector track relay TDB, contact 38 of switch circuit controller SCA in a normal position, upper rail of track B, to the negative terminal of the track battery 13.

With both of the detector track relays TDA and TDB picked up, a pick-up circuit for the stick relay S is closed from the positive terminal of the battery 32, through front contact 40 of detector track relay TDA, front contact 41 of detector track relay TDB, windings of stick relay S, to the negative terminal of battery 32. This circuit is of course normally closed, but whenever it is opened, a stick circuit is effective to maintain the stick relay S energized under certain conditions as will be later explained. For the present, it is sufficient to know that the stick circuit for the relay S may be energized from the positive terminal of the battery 32, through the contact 42 of switch box SCB in a normal position, contact

43 of switch box SCA in a normal position, front contact 44 of relay S, windings of relay S, to the negative terminal of the battery 32.

With the detector track relays TDA and TDB as well as the stick relay S picked up, the right-of-way track circuits for the respective tracks A and B are closed to energize their respective track relays TA and TB.

More specifically, the track relay TA is energized by a circuit closed from the positive terminal of the track battery 5, over the lower rail of track section 6, front contact 50 of detector track relay TDA, wire 51, wire 52, front contact 53 of stick relay S, wire 54, lower rail of track section 7, windings of track relay TA, upper rail of track section 7, wire 55, front contact 56 of stick relay S, wire 58, wire 59, front contacts 60 of detector track relay TDA, upper rail of track section 6, to the negative terminal of battery 5. This energization of the track relay TA closes its front contact 61 so that the west bound signal LA can be cleared subject to the usual signaling controls provided in conventional block signaling circuits.

In a like manner, the track relay TB is energized by a circuit closed from the positive terminal of the track battery 10, upper rail of track section 11, front contact 62 of detector track relay TDB, wire 63, wire 64, front contact 65 of stick relay S, wire 66, upper rail of track section 12, windings of track relay TB, lower rail of section 12, wire 67, front contact 68 of stick relay S, wire 69, wire 70, front contact 71 of detector track relay TDB, lower rail of track section 11, to the negative terminal of the track battery 10. This energization of the track relay TB closes its front contact 72 to provide that the east bound signal RB may be cleared subject to traffic conditions as provided in accordance with conventional block signaling.

It is believed that the characteristics of the invention will be best understood by further description of the track circuit organization being given from the standpoint of operation during the passage of traffic.

For example, let us assume that the signal LA is clear and that a train is proceeding in a west bound direction over track A. When the train enters the track section 7, the track relay TA is shunted by the train so that it opens front contact 61 causing the signal LA to be placed at stop. As this train proceeds into the detector track section DA, the detector track relay TDA is shunted in a manner that will be obvious from the drawing, which causes front contacts 50 and 60 of this relay to be opened removing the connection of the track section 6 with the track section 7. Also, back contacts 50 and 60 are closed providing the double connection of wires 51 and 59 across the wires 52 and 58 to shunt the track section 7. Thus, the track relay TA is assured of continued deenergization to hold the signal LA at stop.

When the train proceeds into the track section 6, the track battery 5 is of course shunted and even though the train has passed out of the detector track section DA and the track relay TDA has picked up, the track relay TA of the right-of-way track circuit is maintained deenergized until such train moves to the left out of the track section 6. It is of course considered that suitable signaling circuits are provided in connection with the signal LA so that even though front contact 61 is again closed, the signal LA will give the proper indications in accordance with the traffic conditions.

During the passage of the west bound train over track A as above pointed out, it is seen that the opening of front contact 40 of the detector track relay TDA does not deenergize the stick relay S, because of its stick circuit including front contact 44 and switchbox contacts 42 and 43. For this reason, the stick relay S is maintained energized and the front contacts 65 and 68 are maintained closed so that the right-of-way track circuit including track relay TB for track B is not affected by the passage of a west bound train on track A.

It will be understood by analogy that a similar operation takes place upon the passage of an east bound train over the track B without in any way affecting the track circuits of the track A. This is for a similar reason, since the opening of front contact 41 while a train is passing over detector track section TB does not deenergize the stick relay S because its stick circuit is still closed.

Should an east bound train be on the detector track section DB at the same time that a west bound train is proceeding over the detector track section DA, both detector track relays TDB and TDA would be deenergized opening their front contacts 41 and 40 respectively. However, under such a traffic condition the stick relay S is not released by reason of the continued energization of its stick circuit. This is a necessary requirement since the east bound train might remain on the detector track section DB for some time after the west bound train has proceeded well beyond the point in the stretch of track where it would cause the signal LA to remain at stop or caution; and if it were not for the stick circuit of the relay S, the presence of the train on the section DB would maintain the relay S deenergized which in turn would undesirably hold the signal LA at stop. Thus, it is seen that the control of traffic on the tracks A and B is entirely independent while the track switches SA and SB are continuously maintained in their normal positions.

Let us assume by way of example that an east bound train on the track B desires to make a switching movement over the crossover onto the track A. Such a train would of course pass over the track sections 12, DB and 11 causing the signal RB to go to stop in the usual way. The trainman then operates the track switch SB to its reverse position so that the train can proceed over the crossover. As soon as contacts 35 and 37 are opened, the detector track relays TDA and TDB are both deenergized. The opening of their front contacts 40 and 41 allows the stick relay S to drop away since its stick circuit is also opened at switch box contact 42. As the train passes over the crossover its wheels would continue to shunt the track so that the track relay TDB would remain dropped away until the train has passed beyond the insulated joints 23 even if the track switch SB were restored to normal. It will of course be understood that, when the train is to the left of insulated joints 23, the detector track relay TDA is shunted and drops away. It may be that the trainman will restore the track switch SB to its normal position before operating the track switch SA to its reverse position, as might happen with a very short train or with a locomotive on a long crossover; but, even though the switch box contacts of switch box SCB are restored to their normal positions, the detector track relay TDA remains deenergized due to the train shunting the detector track section DA. Also, detector track relay TDB may be picked up

since the switch box contact 37 is restored to its normal position, but the stick relay S remains deenergized since the contact 40 of the detector track relay TDA is opened. Under this condition, the track relay TB for the right-of-way track circuit of the track B will remain deenergized since the open condition of front contacts 65 and 68 of the stick relay S removes the connection of the track section 11 with the track section 12. Also, back contacts 65 and 68 complete a circuit through wires 66 and 67 to shunt the track relay TB.

The trainman may then operate the track switch SA to its reverse position and the train 15 proceed onto the track A, it being noted that the signal LA is held at stop because of the deenergization of the stick relay S as well as the de-energization of the detector track relay TDA and track relay TA from the time of the initial 20 opening of the track switch SB until the train has moved westwardly beyond the track section 6. When the train has traveled to the left out of the detector track section DA so that both of the detector track relays TDA and TDB are 25 picked up with both track switches SB and SA in normal positions, the pick up circuit for the stick relay S is closed and the track relay TB for track B is rendered dependent upon the traffic conditions of track B alone, but the track relay TA is not re-energized until the train moves to 30 the left out of track section 6.

In view of the above, it will be evident that the signals of two adjacent parallel tracks are independent of each other until the switches of the crossover are initially operated to reverse positions, and thereafter the signals for both tracks are held at stop independently of the position of the track switches until both detector track circuits associated with the switches become uncoupled. In this way, it is impossible for a train or a locomotive to remain standing on the crossover with both switches normal without holding the signals on both tracks at stop. This avoids any possibility of a train moving over the crossover from fouling or interfering with the passage of a train on the main track it has just left, because traffic is held up on such track until the right of way is established as being safe.

As above mentioned, with the detector track 45 circuits thus organized, the turnout fouling rail at each end of the crossover and associated with its respective switch, is included in the associated detector track section in series therewith in such a way as to provide broken rail protection, that is, if this turnout fouling rail should become broken, the associated detector track section would be interrupted and thus betray the condition by reason of the continued deenergization of the associate detector track relay.

In the particular arrangement chosen for the embodiment of the present invention, the condition of the detector track circuits adjacent the opposite ends of the crossover as well as the condition of the stick relay acts through the medium 60 of the track circuits of the right-of-way to hold the respective signals LA and RB at stop without the use of additional line wires for this purpose. Also, it is assumed that each of the signals is provided with line circuit control which is governed in accordance with traffic conditions in advance so as to give the proper signal indications in accordance with the presence of trains in track sections in advance. It will be appreciated 65 that this manner of imposing the detector track circuit conditions and the associated stick relay 70

condition upon the signals is particularly useful and adaptable in connection with coded track circuits where there are no line wires involved. However, it should be understood that in some cases it may be desirable to omit the detector track circuit control from the right-of-way track circuits and include such control in the signaling line circuit. In other words, the line circuit for signal R&B for example would include front contacts of the relays TDB and S in a manner similar to that in which the circuit for relay TB is controlled by such relays. This is mentioned so as to bring out that the principles of the invention relating to the novel way in which the detector track circuits for the opposite ends of a crossover are interrelated may be applied to various types of signaling systems and still be within the scope of the present invention.

Having thus described a track circuit organization for a crossover as one specific embodiment of the present invention, it is desired to be understood that this form is selected to facilitate in the disclosure of the invention rather than to limit the number of forms which it might assume; and, it is to be further understood that various modifications, adaptations, and alterations may be applied to the specific form shown to meet the requirements of practice, without in any manner departing from the spirit or scope of the present invention, except as limited by the appended claims.

What I claim is:

1. In combination, two parallel railway tracks, each provided with an insulated track section, a crossover having a track switch at each end for connecting said two track sections, a track circuit for each section including the rails of the section and the rails of said crossover on the adjoining side of a common intermediate point in said crossover, as well as the usual track relay and a source of track circuit current, and means operating when either or both of said switches of said crossover are reversed for opening the track circuit for each of said sections.

2. In combination, two parallel railway tracks each provided with an insulated track section, a crossover having a track switch at each end for connecting said two track sections, insulating joints for segregating the turnout fouling rails of said crossover from said track sections, a track circuit for each section including the rails of its section and its associated turnout fouling rail of said crossover in series with the usual track relay and a source of track circuit current, and means operating when either or both of said track switches of said crossover are reversed for opening the track circuit for both track sections.

3. In combination, two parallel railway tracks each provided with an insulated track section, a crossover having a track switch at each end for connecting said two track sections, a track circuit for each section including the rails of the section and the rails of said crossover on the adjoining side of a common intermediate point of said crossover as well as the usual track relay and a source of track circuit current, means acting when either or both of said track switches of said crossover are operated to reverse positions for traffic movement over the crossover to deenergize both of said track relays, a stick relay having a pick-up circuit closed only when both of said track relays are energized and having a stick circuit including contacts opened whenever either one or both of said track switches is operated to reverse positions, and signal control circuits for each track controlled

ble to allow the passage of traffic on its track only providing said stick relay is energized.

4. In combination, two parallel railway tracks each provided with an insulated track section, a crossover having a track switch at each end for connecting said two track sections, insulating joints for isolating the turnout fouling track rails of said crossover from said sections, a track circuit for each section including the rails of its section and its associated turnout fouling rail of said crossover in series with the usual track relay and source of track circuit current, means acting when the track switches of said crossover are operated to reverse positions to deenergize both of said track relays, a stick relay having a pick-up circuit including front contacts of said track relays and having a stick circuit including contacts opened whenever either or both of said track switches are operated to reverse positions, and signal control means for each track governed to allow the passage of traffic over that track only providing said stick relay is picked up.

5. In a railway signaling system for two parallel railway tracks, adjacent insulated track sections on each track, a crossover having a track switch at each end for connecting said two adjacent track sections, manually operable means for individually operating each track switch, insulated joints for isolating the two turnout fouling rails of said crossover from said track sections, a track circuit for each section including the rails of its section and one turnout fouling rail of said crossover in series with the usual track relay and a source of track circuit current, and means associated with said switches for opening said track circuits when either of said switches is manually operated to a reverse position for allowing the passage of traffic over said crossover.

6. In combination, two parallel railway tracks each provided with an insulated track section, a crossover having a track switch at each end for connecting said two track sections, each of said switches including the usual frog for one of the rails of the crossover, an insulated joint in each rail of said crossover at an intermediate point, circuit means connecting the section of crossover rail adjacent a switch frog to the main rail of the associated track section including that frog, an insulated joint in the turnout stock rail near the switch at each end of said crossover so as to provide a segregated turnout fouling rail section in opposite rails of the crossover on opposite sides of said intermediate point, and a track circuit for each section including the rails of its section and the turnout fouling rail section of said crossover next adjacent its switch in series with a track relay and a source of track circuit energy, whereby a train passing over said crossover shunts the track relay of each section until the train passes said intermediate point in the crossover.

7. In combination, two parallel railway tracks each provided with an insulated track section, a crossover having a track switch at each end for connecting said two track sections, each of said switches including the usual frog for one of the rails of the crossover, an insulated joint in each rail of said crossover at an intermediate point, circuit means connecting the section of crossover rail adjacent a switch frog to the main rail of the associated track section including that frog, an insulated joint in the turnout stock rail near the switch at each end of said crossover so as to provide a segregated rail section in opposite rails of the crossover on opposite sides of said intermediate point, a track circuit for each section in-

cluding the rails of its section and the segregated rail section of said crossover next adjacent its switch in series with a track relay and a source of track circuit energy, whereby a train passing over said crossover shunts the track relay of each section until the train passes said intermediate point in the crossover, a stick relay having a pick up circuit including front contacts of the track relay for each of said two sections and having a stick circuit including contacts opened whenever either or both of said track switches are operated to their reverse positions, and signal control means for each parallel track rendered effective to allow the passage of traffic only providing said stick relay is energized.

8. In combination, two parallel railway tracks each provided with an insulated detector track section, a crossover having a track switch at each end for connecting said two detector track sections, each of said switches including the usual frog for one of the rails of the crossover, an insulated joint in each rail of said crossover at an intermediate point, circuit means connecting the section of crossover rail adjacent a switch frog to the main rail of the associated track section including that frog, an insulated joint in the turnout stock rail near the switch at each end of said crossover so as to provide a segregated rail section in opposite rails of the crossover on opposite sides of said intermediate point, a track circuit for each detector track section including the rails of its section and the insulated rail section of said crossover next adjacent its switch in series with a detector track relay and a source of track circuit energy, whereby a train passing over said crossover shunts the detector track relay of each detector track section until the train passes said intermediate point in the crossover, track sections at the opposite ends of each of said detector track sections included in a track circuit for its track, such track circuit having a track relay and a track battery at the extreme ends of the two sections forming the track circuit, a stick relay having a pick up circuit including front contacts of said detector track relays of said detector track sections and having a stick circuit including contacts open whenever either one or both of said switches is operated to reverse positions, and circuit means for connecting the near ends of the track sections on each side of a detector track section for each track and including front contacts of said stick relay.

9. In a track circuit organization for a crossover connecting two parallel tracks, a detector track section associated with each of the track switches at the opposite ends of the crossover, a stick relay acting when deenergized to cause the

signals for both tracks to be held at stop, pick up circuit means for said stick relay closed only providing both of said detector track sections are unoccupied, and stick circuit means for said stick relay opened when either of the track switches at the opposite end of the crossover is operated to a reverse position, whereby the contemporaneous operation of a track switch to a reverse position with the occupied condition of either detector track section causes the signals for both tracks to be held at stop until both detector track sections become unoccupied irrespective of the prior return of both track switches to their normal positions.

10. In a track circuit organization for a crossover connecting two parallel tracks with signals for governing traffic over each of the tracks, a detector track section associated with each of the track switches at the opposite ends of the crossover, a stick relay, circuit means for the signal of each track for allowing such signal to be cleared only providing said stick relay is energized and the detector track section of the associated track is unoccupied, a normally energized stick circuit means for said stick relay de-energized when either of the track switches at the ends of the crossover is operated to a reverse position, and pick-up circuit means for effecting the reenergization of said stick relay only providing there is no train occupying said crossover, whereby the operation of either track switch to a reverse position causes the signals for both tracks to be held at stop until said crossover is unoccupied irrespective of the return of that track switch of the crossover to its normal position.

11. In combination, two parallel railway tracks each provided with an insulated track section, a crossover having a track switch at each end for connecting said two track sections, a signal associated with each of said track sections, a track circuit for each section including the rails of that section and the rails of said crossover on the adjoining side of a common intermediate point of said crossover as well as the usual track relay and source of track circuit current, means effective when either or both of said track switches of said crossover are operated to reversed positions for opening both said track circuits and for holding both said signals at stop, and means initially conditioned by the operation of either or both said switches to reverse positions for requiring both said track sections to be unoccupied subsequent to the restoration of both said switches to their normal positions before either of said signals can be cleared.

ANDREW LANGDON.
